UNITED STATES PATENT OFFICE.

WILLIAM JAMES HANDS, OF TORONTO, ONTARIO, CANADA.

CLUTCH.

No. 851,986.

Specification of Letters Patent.

Patented April 30, 1907.

Application filed August 27, 1906. Serial No. 332,152.

To all whom it may concern:

Be it known that I, WILLIAM JAMES HANDS, a subject of the King of Great Britain, residing at Toronto, county of York, in the Province of Ontario, Canada, have invented certain new and useful Improvements in Clutches; and I do hereby declare that the following is a full, clear, and exact description of the invention, such as will enable others skilled in the art to which it appertains to make and use the same.

My invention relates to clutches; the object of my invention is to provide a clutch adapted to transmit a rotary movement in two directions from a driving shaft to a driven shaft, and to provide means for adjusting the clutch to permit movement of the driving shaft without moving the driven shaft; and, my invention consists of the construction, combination and arrangement of parts, as herein illustrated, described and claimed.

In the accompanying drawings, forming part of this application, I have illustrated one form of embodiment of my invention, in which drawings similar reference characters designate corresponding parts, and in which:

The figure is a longitudinal vertical section through the upper portion of the device, and showing the shafts and adjusting lever in elevation.

Referring to the drawings, 1 designates a two-part casing, adapted to contain the mechanism hereinafter described.

A suitably supported driving shaft 2 has its free end projecting into the casing 1, and the driven shaft 3 has its free end projecting into the casing adjacent the end of the driving shaft 2. A suitable sleeve of bearing metal 4 is disposed between the casing 1 and the driving shaft 2.

Secured to the driving shaft 2, within the casing 1, is a hub 5, provided with a flange 6 inclined toward the free end of the shaft 2, and continued outward from the shaft into a vertical flange 7, having on one of its faces a lug 8. The vertical flange 7 is continued into a horizontal flange 9, which is stiffened by an annular web 10. The horizontal flange 9 has projecting therefrom a vertical flange 11, for a purpose hereinafter described.

An annulus 12 is secured to the vertical flange 7, as by means of the screws 13, having its edge abutting against the lug 8. The annular member 12 is provided with a flange 14, projecting therefrom at an angle to the axis of the driving shaft 2.

Slidably disposed on the end of the driven shaft 3, is a hub 15, fixed from rotation on the shaft 3 as by means of the spline 16. The hub 15 is provided with a flange 17 inclined 60 toward the flange 6 on the hub 5, and is extended into a vertical portion 18 provided with a lug 19 thereon. Disposed on the vertical portion 18 of the flange 17 is an annulus 20, abutting against the lug 19, and maintained in position as by means of the screw 21.

The annulus 20 is provided with a flange 22, disposed at an angle to the axis of the driving shaft 2, and at an opposite angle to the flange 14, so that when the flanges 14 and 22 are brought together they exactly coincide. The flanges 14 and 22 being in engagement, and the shaft 2 being rotated in the direction indicated by the arrow 23, the driven shaft 3 will be caused to rotate in the direction indicated by the arrow 24.

The hub 5 is provided with an interior shoulder 25, and the hub 15 is provided with a shoulder 26. Disposed on these hubs intermediate of the shoulders 25 and 26, is a sleeve 27, adapted to bridge the space between the hubs and between the shafts 2 and 3. The shoulder 25 is adapted to receive the contact of the end of the sleeve 27, and to limit the movement of the hub 15 when it is slidably adjusted on the shaft 3, as herein-after described. Disposed around the adjacent ends of the shafts 2 and 3, and adapted to ride on the sleeve 27, is a helical spring 28, the thrust of which normally maintains the flanges 14 and 22 in contact, so that the driven shaft 3 will rotate as described. A bearing ring 29 is slidably disposed on the sleeve 27, adjacent one end of and adapted to receive the thrust of the spring 28. Disposed adjacent the bearing ring 29 are balls 30, and adjacent the balls 30 is a second bearing ring 31, held on the shoulder 26 of the hub 15. The plate 29 is adapted to receive the thrust of the spring 28, so that the hub 15 will rotate without rotating the spring.

Slidably disposed on the shaft 3, and bearing against the outer end of the hub 15, is a bearing ring 32, adjacent which are disposed balls 33, and adapted to bear on the balls and slidably disposed on the shaft 3 is a second bearing ring 34. Slidably disposed on the shaft 3 is a sleeve 35, the end of which bears against the bearing ring 34 and forms a bearing for the casing 1, corresponding to the bearing 4 on the opposite side of the casing.

A lever 36 is pivoted as at 37 to an arm 38,

which may be secured adjacent thereto in any suitable manner. The lever is secured to the sleeve 35 as by the pin 38^a, so that when the lever is in the full line position, the flanges 14 and 22 are in engagement, and the shaft 3 will rotate in the same direction as the shaft 2. By adjusting the lever to the vertical dotted line position, the sleeve 35 is moved on the shaft 3, thereby sliding the hub 15, and partly compressing the spring 28, until the flanges 14 and 22 are thrown out of engagement, and the shaft 2 will rotate without rotating the shaft 3. The vertical flange 18 of the hub 15 is provided with a horizontal flange 39, which is stiffened by the web 39^a, and carries a vertical flange 40.

The upper portion of the casing 1 is provided with a thickened portion 41, through which is projected a non-rotatable stud 42, maintained in position by means of the nut 43. Disposed on the stud 42 adjacent the thickened portion 41, is a bearing plate 44, adapted to receive the upward thrust of the upper bearing cone 45, there being a corresponding lower bearing cone 45 adjacent the lower end of the stud. Upper and lower bearing rings 46 are disposed adjacent the cones, and are adapted to maintain in position the balls 46^a, so that the bearing rings 46 may be freely rotated around the stud 42. Secured to or formed integral with the bearing rings 46, are angle iron annular members 47, which carry the annular member 48, which is maintained in position as by means of the screws 49. This annular bearing 48 is engaged by a vertical flange 11 of the hub 5, when the lever 36 is moved to the inclined dotted line position, thus imparting a rotary motion to the member 48. When the lever 36 is in this position, the shoulder 52 of the sleeve 35 contacts with the casing 1, which is mounted on the shafts 2 and 3 to permit a slight longitudinal movement, so as to make the contact between the flange 11 and annulus 48.

When the lever 36 is thrown to the inclined dotted line position, the flange 40 of the hub 15 contacts with the annular member 48, and causes rotation of the shaft 3 in the direction indicated by the arrow 50, which is reverse to the rotation of the driving shaft 2.

A suitable oil-tight cover or plate 51 is secured to the angle members 47, and is adapted to maintain a lubricant on the bearing parts adjacent thereto.

Having thus fully described my invention, what I claim as new and desire to secure by Letters Patent is:—

1. In a clutch, the combination comprising a casing, a driving shaft projecting into the casing, a driven shaft projected into the casing, a clutch member secured to the driving shaft, a clutch member slidably disposed to rotate with the driven shaft, means normally maintaining the clutch members in en-

gagement, means for throwing the clutch members out of engagement, and a rotatable member carried by the casing and adapted to connect the clutch members to cause reverse movement of the driven shaft.

2. In a clutch, the combination comprising a driving shaft, a driven shaft, a hub fixed on the driving shaft and provided with an inclined flange, a hub slidably disposed to rotate with the driven shaft and provided with an inclined flange adapted to contact with the flange of the other hub, means adapted to normally maintain the flanges in engagement, means for separating the slideable hub from the fixed hub to separate said flanges, and means for connecting a part of the fixed hub with a part of the slideable hub for reverse movement of the latter.

3. In a clutch, the combination comprising a driving shaft, a driven shaft, a hub fixed on the driving shaft and provided with an inclined flange, a hub slidably disposed to rotate with the driven shaft and provided with an inclined flange adapted to contact with the flange of the other hub, a coil spring disposed around the hubs, means for separating the slideable hub from the fixed hub to separate said flanges, and means for connecting a part of the fixed hub with a part of the slideable hub for reverse movement of the latter.

4. In a clutch, the combination comprising a driving shaft, a driven shaft, a hub fixed on the driving shaft and provided with an inclined flange, a hub slidably disposed to rotate with the driven shaft and provided with an inclined flange adapted to contact with the flange of the other hub, means adapted to normally maintain the flanges in engagement, means for separating the slideable hub from the fixed hub to separate said flanges, means for bridging the space between the hubs and limiting the movement of the slideable hub in one direction, and means for connecting a part of the fixed hub with a part of the slideable hub for reverse movement of the latter.

5. In a clutch, the combination comprising a driving shaft, a driven shaft, a hub fixed on the driving shaft and provided with an inclined flange and provided with a shoulder, a hub slidably disposed on and fixed to rotate with the driven shaft and provided with an inclined flange adapted to contact with the inclined flange of the other hub, and provided with a shoulder, means adapted to normally maintain the inclined flanges in engagement, means for separating the slideable hub from the fixed hub to separate the inclined flanges, a sleeve disposed around the hub between said shoulders, and means for connecting a part of the fixed and slideable hubs for reverse movement of the latter.

6. In a clutch, the combination comprising a driving shaft, a driven shaft, a hub fixed on the driving shaft and provided with an in-

clined flange; a hub slidably disposed to rotate with the driven shaft and provided with an inclined flange adapted to contact with the flange of the other hub; a coil spring disposed around the hubs, bearing rings disposed around one of the hubs against one of which bearing rings the coil spring is arranged to thrust, friction reducing members disposed between the rings, means for separating the 5 said hub from the fixed hub to separate said flanges, and means for connecting a part of the fixed hub with a part of the slidable hub for reverse movement of the latter.

7. In a clutch, the combination comprising 15 a driving shaft, a driven shaft, a clutch member secured on the driving shaft, a clutch member slidable on and fixed to rotate with the driving shaft, flanged members secured on the clutch members, means adapted to 20 normally maintain said flanged members in contact with each other, means for separating the flanged members, and rotatable means adapted to connect a portion of the clutch members for reverse rotation of one of 25 said members.

8. In a clutch, the combination comprising 30 a driving shaft, a driven shaft, a clutch member secured on the driving shaft and provided with a lug thereon, a clutch member slidable on and fixed to rotate with the driven shaft and provided with a lug thereon, flanged members disposed on the clutch 35 members in contact with said lugs, screws adapted to secure the flanged members in position, means adapted to normally maintain the flanged members in contact with each other, means for separating the flanged members, and rotatable means adapted to 40 connect the clutch members for reverse rotation of one of them.

9. In a clutch, the combination comprising 45 a driving shaft, a driven shaft, a clutch member secured on the driving shaft, a clutch member slidable on and fixed to rotate with the driven shaft, flanged members secured to the clutch members, means adapted 50 normally to maintain said flanged members in contact with each other, a sleeve slidably disposed on the driven shaft and arranged to move the slidable clutch member, a lever pivoted adjacent the sleeve and secured thereto, and rotatable means adapted to 55 connect a portion of the clutch members for reverse rotation of one of them.

10. In a clutch, the combination comprising 60 a driving shaft, a driven shaft, a clutch member secured on the driving shaft, a clutch member slidable on and fixed to rotate with the driven shaft, flanged members 65 secured to the clutch members, means adapted normally to maintain said flanged members in contact with each other, a sleeve slidably disposed on the driven shaft and arranged to move the slidable clutch member, bearing rings interposed between the sleeve 70

and the slidable clutch member, friction reducing members disposed between the bearing rings, a lever pivoted adjacent the sleeve and secured thereto, and rotatable means adapted to connect a portion of the clutch 75 members for reverse rotation of one of them.

11. In a clutch, the combination comprising 80 a casing, a driven shaft projected into the casing, a driving shaft projected into the casing, a hub fixed on the driving shaft and provided with a peripheral flange, an annulus secured to the hub adjacent the flange, an inclined flange on the annulus, a hub slidably disposed and fixed to rotate with the driven shaft and provided with a peripheral flange, 85 an annulus on said latter hub adjacent its flange and provided with an inclined flange, means normally maintaining the inclined flanges in contact, means for separating the inclined flanges, and means for connecting 90 the peripheral flanges of the hubs.

12. In a clutch, the combination comprising 95 a casing, a driven shaft projected into the casing, a driving shaft projected into the casing, a hub fixed on the driving shaft and provided with a peripheral flange, an annulus secured to the hub adjacent the flange, an inclined flange on the annulus, a hub slidably disposed and fixed to rotate with the driven shaft and provided with a peripheral flange, 100 an annulus on said latter hub adjacent its flange and provided with an inclined flange, means normally maintaining the inclined flanges in contact, means for separating the inclined flanges, and rotatable means for connecting 105 the peripheral flanges of the hubs when the inclined flanges are sufficiently separated.

13. In a clutch, the combination comprising 110 a casing, a driven shaft projected into the casing, a driving shaft projected into the casing, a hub fixed on the driving shaft and provided with a peripheral flange, an annulus secured to the hub adjacent the flange, an inclined flange on the annulus, a hub slidably disposed on and fixed to rotate with the driven shaft and provided with a peripheral flange, 115 an annulus on said latter hub adjacent its flange and provided with an inclined flange, means normally maintaining the inclined flanges in contact, means for separating the inclined flanges, a stud carried by the casing and provided with bearing cones, annular angle iron members disposed around the stud, bearing rings carried by the annular angle iron members, friction reducing means disposed between the bearing rings and the cones, and an annular friction member carried by the angle iron members and disposed in contact with said peripheral flanges when the inclined flanges are widely separated.

14. In a clutch, the combination comprising 120 a casing, a driven shaft projected into the casing, a driving shaft projected into the cas- 125

ing, a hub fixed on the driving shaft and provided with a peripheral flange, an annulus secured to the hub adjacent the flange, an inclined flange on the annulus, a hub slidably disposed on and fixed to rotate with the driven shaft and provided with a peripheral flange, an annulus on said latter hub adjacent its flange and provided with an inclined flange, means normally maintaining the inclined flanges in contact, means for separat-

ing the inclined flanges, and means for connecting the peripheral flanges of the hubs, and an oil-retaining member secured to the rotatable connecting means.

In witness whereof I have hereunto set my hand in the presence of two witnesses.

WILLIAM JAMES HANDS.
